By C. M. Alexander.

UNITED STATES PATENT OFFICE.

JAMES C. COVERT, OF WEST TROY, NEW YORK.

HARNESS ATTACHMENT.

SPECIFICATION forming part of Letters Patent No. 244,555, dated July 19, 1881.

Application filed May 2, 1881. (Model.)

To all whom it may concern:

Be it known that I, JAMES C. COVERT, of West Troy, in the county of Albany, and in the State of New York, have invented certain new and useful Improvements in Harness Attachments; and I do hereby declare that the following is a full, clear, and exact description thereof, reference being had to the accompanying drawings, and to the letters of reference 5 marked thereon, making a part of this specification.

This invention relates to a fastening device for attachment to the end of a rope to enable it to be adjustably secured at any intermediate point of the main portion, its object being to dispense with the use of screw-thimbles and other devices used for a like purpose, and to obviate the knotting of ropes to guarantee the maintenance of a rope-end in the position to 15 which adjusted, and to facilitate the adjustment of the same.

In the accompanying drawings, Figure 1 illustrates the application of my invention to a halter in use. Fig. 2 is a perspective view 25 of a halter provided with my improved fastening device. Fig. 3 shows an edge and a face view of a modification of the fastening. Fig. 4 is a perspective view of another modification; Fig. 5, a like view, showing only two apertures.

Referring to figures, the letter A denotes a 30 flat plate of metal oblong in shape and having formed through it a longitudinal series of four adjacent holes, B. Near one end of the plate a loop, C, formed in one piece with the plate, 35 projects laterally, and has loosely engaged with it the shank of a snap-hook, D. The main portion or body of the halter E is twined back and forth through the first three holes, 40 commencing at the loop end, and with the hole at the other end is engaged the hook of a snap-hook, D', the shank of which is firmly secured to the end of the halter. This snap-hook D' merely serves as a means of attaching the 45 plate A to the halter end to enable it to be readily detached therefrom, if desired. The plate might be attached directly to the halter end, the same as is the snap-hook, by bending said end through the end hole of the plate and making it fast. The object of the snap-hook 50 D is to connect the plate with one of the bit-

rings, in order to hold the halter-loop well forward and off the animal's throat.

In the case of a halter the snap-hook D' very much facilitates its application and removal; but it is obvious that if the halter end were attached directly to the plate the loop might be enlarged by loosening the halter in the holes in the plate and slipping said plate along. This slipping along can only be effected by bending the rope so as to move transversely 55 with respect to the plate, for whenever the halter is subjected to longitudinal strain it is gripped firmly by the partitions between the holes and the end walls thereof, and the more strain there is put upon it the tighter it is held, 60 the friction between it and the several surfaces against which it is forced in different directions being so great as to effectually prevent its slipping, and the only way to decrease this friction is to decrease the force which occasions it, that is, to relieve the strain upon the 65 halter and ease up its tortuous course through the holes of the plate when said plate may be adjusted, as desired.

Neither of the snap-hooks shown in Fig. 2 70 is absolutely necessary, as the halter end may be attached directly to one end of the plate, and when a loop of proper size is formed around the animal's neck there is no danger of choking by the tightening of said loop, as the plate 75 cannot slip upon the halter under any strain to which the animal can possibly subject it. The simple form of the fastening shown in Fig. 3 will therefore be found quite efficient as a 80 halter-fastening, or securing the end of any 85 other rope firmly, though adjustably, at any intermediate point of the main portion. In this form of the device I prefer to bend slightly in opposite directions, as shown in Fig. 3, the 90 end portions *a a* of the plate through which the respective end holes are formed, as thereby the ends of the plate are caused to bend the halter at a sharper angle, and consequently increase the frictional resistance to its longitudinal movement under strain.

In the modification shown in Fig. 4 I substitute a hook, F, for one of the end holes or loops in the plate A', this form of my invention being especially designed for application 95 to hammock-cords, in which the hook F will 100

be detachably engaged with a ring or loop at the end of the cord, the main portion of which will be passed back and forth through two or more of the holes.

5 It has been customary in halters to fix at an intermediate point a surrounding thimble having a projecting loop or eye, with which a hook attached to the halter end is to be engaged, the said loop or eye being formed on a screw-
10 shank, which is inserted through the wall of the thimble, so that its tip will clamp the halter when screwed inwardly, and some halters are provided with another similar thimble and screw-loop having a snap attached for engagement with the bit-ring. These devices are
15 more or less injurious to the halter, expensive, and troublesome to adjust.

The economy and convenience of my improved fastening in being formed in one piece and
20 grasping the rope at several points, whereby, undue pressure in any particular place is prevented will be apparent.

What I claim is—

1. A halter provided with a plate, A, having a series of openings in which the rope may 25 be tortuously threaded through, and an end ring or opening to which one end of the rope may be attached, whereby an adjustable loop is made for the neck of the animal, substantially as specified.

2. A metallic halter-plate having a succession of openings for the tortuous passage of a rope, and provided with an eye upon one edge to receive a snap-hook or other fastening, substantially as set forth.

In testimony whereof I affix my signature, in presence of two witnesses, this 16th day of April, 1881.

JAMES C. COVERT.
